UNITED STATES PATENT OFFICE.

HERMAN C. F. E. SNOWMAN, OF NEW PALTZ, ASSIGNOR TO THE NEW YORK
LABOR SAVING PATENTS EXPLOITING COMPANY, OF NEW YORK, N. Y.

ENVELOPE.

SPECIFICATION forming part of Letters Patent No. 531,281, dated December 18, 1894.

Application filed January 31, 1894. Serial No. 498,553. (No model.)

To all whom it may concern:

Be it known that I, HERMAN C. F. E. SNOWMAN, a citizen of the United States, residing at New Paltz, in the county of Ulster and State of New York, have invented certain new and useful Improvements in Envelopes, of which the following is a specification.

My invention has relation to mailing envelopes; and it relates particularly to the specific arrangement of an envelope, whereby when sealed tampering therewith may be readily detected.

The principal object of my invention is to provide a simple, inexpensive and effective envelope adapted to contain registered or other mail matter having an aniline colored or coated slip or tag interposed between the sealed flap and the complementary sealing flap of the mail parcel and so arranged as that in the event of steaming, moistening or tampering therewith for the purpose of unwarrantably opening the letter or parcel, the same may be readily detected.

My invention consists of the improvements in an envelope hereinafter described and pointed out in the claim.

The nature and scope of my invention will be understood from the accompanying drawing forming part hereof, and illustrating in rear elevation an envelope with the specific form or shape of a detector and distributor of my invention interposed between the sealed and sealing perforated flaps of the envelope.

Referring to the drawings *a*, is an ordinary form of envelope provided with imperforate side flaps *b* and *b'*, and with a bottom cone-shaped overlapping flap *c*, which normally engages the respective imperforate flaps *b* and *b'*, and is sealed thereto. This flap *c*, is provided along the surface thereof adjacent to the upper edges of the same with a series of perforations *e²*, and at the apex portion of the flap with a cluster of perforations *e⁴*, for a purpose to be presently explained.

d, is the cone-shaped top sealing flap of the envelope having the under surface adjacent to the edge thereof gummed and with perforations *e'*, extending therethrough and with a cluster of such perforations *e³*, at the apex portion of the flap.

Interposed between the bottom sealed flap *c*, and the top sealing flap *d*, is an aniline colored or coated tag or slip *E*, of tissue paper or other material forming what I term

the "detector and distributor" of my invention, whereby when the respective flaps of the envelope are sealed with mail matter therein, tampering or any attempt to abstract matter in the same, by steaming or otherwise loosening the sealed or sealing flaps of the envelope can be readily detected, through distribution of the aniline color or coating of the detector over the surfaces of the envelope and into the pores of the material of the envelope, but, however, without coming in contact with the mail matter contained therein.

It may be here remarked that the color of the detector is indelibly stamped or impressed into the envelope, and thus is presented a safe and entirely reliable parcel for the carriage of mail matter. This detector and distributor *E*, as hereinbefore explained, has a hexagonal body *e*, with four inclined arms *e⁵* and *e⁶*, which extends from the body *e*, and respectively engage with the side flap *b* and *b'*, and with the under surface of the sealing and sealed perforated flaps *c* and *d*, of the envelope, as illustrated, so as to render it possible to detect at a glance whether any tampering by the application of steam or any other means has been had with the envelope to abstract the contents of the envelope.

Having thus described the nature and objects of my invention, what I claim as new, and desire to secure by Letters Patent, is—

An envelope provided with imperforate side flaps, a bottom cone-shaped sealed flap with perforations arranged adjacent to the upper edges thereof and at the apex portion of the same is provided a cluster of perforations, a complementary cone-shaped sealing flap with perforations arranged adjacent to the lower edges and with a cluster of perforations in the apex portion thereof, a hexagonal shaped aniline coated or colored detector and distributor interposed between the perforated sealing and sealed flaps and engaging the imperforate side flaps and provided with inclined coated or colored arms, substantially as and for the purposes set forth.

In testimony whereof I have hereunto set my signature in the presence of two subscribing witnesses.

HERMAN C. F. E. SNOWMAN.
